United States Patent Office

Des. 175,394
Patented Aug. 23, 1955

175,394

WALLET

Edward H. Copen, New York, N. Y.

Application April 26, 1955, Serial No. 35,686

Term of patent 14 years

(Cl. D87—3)

Fig. 1

Fig. 2

I claim:

The ornamental design for a wallet, as shown.
